ABSTRACT

A tamperproof package comprising a container having a neck and an annular radial flange beneath the neck and a plastic closure removably interengaged with the neck. The closure has a top wall and a peripheral skirt. A plastic pilfer band interengages the skirt, such that when the closure is applied to the container, the band is flexed over and engages beneath annular flange on the neck of the container, and when the closure is thereafter removed from the container, the band is prevented from removal from the container and is thereby disengaged from the closure. In a modified form the plastic pilfer band includes an integral liner which is severed from the band and engages the top wall of the closure during assembly of the band to the closure.

TAMPERPROOF PACKAGE

This application is a continuation of Ser. No. 373,911 filed May 3, 1982 now abandoned.

BACKGROUND AND SUMMARY OF THE INVENTION

It is common in packaging goods in containers such as bottles to provide a band or tape between the closure and the container which is broken when the closure is removed thereby giving a visual indication of whether the contents have been tampered with.

It has heretofore been proposed that a separate band be provided on the closure which is separated from the closure when the closure is removed or tampered with. See, for example, U.S. Pat. No. 4,157,144, which shows the use of a ring of U-shaped cross section mounted in the recess of the closure.

Among the objects of the present invention are to provide a tamperproof package which utilizes a plastic closure and a plastic band that is adapted to snap into position in the closure, both the closure and the band being preferably made by injection molding; which will effectively indicate that the contents have been tampered with; and which can be produced with minimum change in the closure.

Among the further objects of the invention are to provide a tamperproof package wherein the plastic band includes an integral liner that is severed from the band and applied in position against the top wall of the closure during assembly of the band to the closure.

In accordance with the invention, a plastic pilfer band interengages the skirt, such that when the closure is applied to the container, the band is flexed over the annular flange of the container causing radially inwardly extending portions of the band to extend below the flange of the container and when the closure is thereafter removed from the container, the band is prevented from removal from the container and is thereby disengaged from the closure. In a modified form, the plastic pilfer band includes an integral liner which is severed from the band and engages the top wall of the closure during assembly of the band to the closure.

DESCRIPTION OF THE DRAWINGS

FIG. 1 is a fragmentary vertical sectional view of a package embodying the invention.

FIG. 2 is a fragmentary sectional view similar to FIG. 1 showing the parts in a different position after the closure has been once removed from the package and reapplied to the package.

FIG. 3 is a fragmentary sectional view of a modified form of package.

FIGS. 4-7 are fragmentary sectional views showing the assembly apparatus in different positions for assembling the band and liner to the closure.

DESCRIPTION

Referring to FIG. 1, the tamperproof package comprises a conventional container 10 such as a bottle of glass or plastic having a neck 11 with an external thread 12 thereon. The package further comprises a closure 13 of organic plastic material such as polypropylene having a top wall 14 and a peripheral wall or skirt 15. The skirt 15 has threads 16 on the internal surface complementary to the threads 12 for holding the closure on the

container. The container includes a flange 17 below the threads 12.

A band 20 in the form of an annular wall 21 with a radially inwardly extending bead 22 is provided and adapted to engage the flange 17, as presently described. The band 20 has portions thereof interengaging with the interior of the skirt 15. More specifically, the inner surface of the skirt 15 includes an annular recess or notch 23 having a downwardly and inwardly inclined surface 23a for receiving an external complementary annular bead 24 on the upper end of the wall 21 of the band 20 having a complementary downwardly and inwardly inclined surface 24a. The band is made of similar organic plastic material, and preferably injection molded. In its unrestrained state prior to insertion or engagement with the closure, the outer diameter of the bead 24 is greater than the inner diameter of the lowermost portion of the wall 15 so that in order to assemble the band on the closure, an axial force must be applied to the lower end of the band to cause the bead 24 to snap into recess 23.

In use, the band 20 is first assembled to the closure 13 and the closure 13 is applied to the container. As the closure with the attached band 20 is threaded on the container 10, the bead 22 snaps over the flange 17 on the container 10 as shown in FIG. 1. Upon removal of the closure by unthreading from the neck, the band 20 is restrained against upward movement by interengagement of the flange 17 and bead 22 so that the band snaps out of engagement with the closure as shown in FIG. 2 by movement of surface 24a along surface 23a, thus indicating that the closure has been tampered with.

It can thus be seen that the tamperproof package utilizes a plastic closure and a plastic band which effectively indicates that the contents have been tampered with. The closure and band can be made of different colors as desired.

In the form of the invention shown in FIG. 3, the package includes a plastic liner 25 interposed between the undersurface of the top wall 14a and the top edge of the container neck 11. The liner 25 is formed as an integral part of the band 20a and is severed from the band and placed in position against the undersurface of the top wall 14a, as presently described.

Referring to FIGS. 4-7, the apparatus for assembling the band 20a with the liner 25 connected by a weakened or thinner portion 26 in the closure comprises a plurality of dies including a first die 27 that has a surface 28 tapered upwardly and inwardly, a second die 29 that is adapted to engage the periphery of the end of the band 20a, a third die 30 that comprises a knife for severing at the weakened portion 26 and a plunger die 31 for pushing the severed liner 25 up into position adjacent the top wall 14a.

In use, the band 20a with the integral liner 25 is placed in position as shown in FIG. 4, and the dies 29, 30, 31 are moved upwardly together causing the upper edge of the band 20a to engage the surface 28 radially compressing the band inwardly whereupon the die 28 is retracted permitting the bead 24 to snap outwardly into engagement with the notch 23 on the closure (FIG. 5). The knife die 30 is then moved upwardly severing the liner 25 from the remainder of the band 20a (FIG. 6) and the plunger die 31 is then moved upwardly to carry the liner 25 into position adjacent the undersurface of the top wall 14a (FIG. 7). The closure includes a small annular bead 32 on the inner surface of the skirt thereof which retains the liner 25 in position.

Where the closure does not utilize a liner, the apparatus is similar except that the knife die 30 and plunger die 31 are not used.

We claim:

1. A tamperproof package comprising
a container having a neck and a radial flange beneath
the neck,
and a plastic closure,
said closure having a top wall and a peripheral skirt,
interengaging means between the closure and the
neck,
a separate plastic pilfer band,
axially engageable and disengageable interengaging
portions between said band and said skirt operable
upon relative axial movement to engage and disen-
gage the skirt and band,
said band having radially inwardly extending por-
tions adapted to extend below the flange of the
container such that when the closure is applied to
the container, the band is flexed over the annular
flange of the container, and when the closure is
thereafter removed from the container, the band is
prevented from removal from the container and is
thereby disengaged from the closure,
said interengaging portions between said skirt of said
closure and said band comprising an annular notch
on the inner surface of said skirt facing radially
inwardly,
said band having an annular band on the outer surface
engaging said notch,
the outer diameter of the bead being greater than the
inner diameter of the portion of the wall having the
notch therein and being such that the band must be
compressed radially inwardly to apply the band to
the closure so that the band has an interference fit
with the skirt of the closure in order that in the
unrestrained position of said band, after the band
has been disengaged from the closure, it cannot
re-engage with the skirt upon re-engagement of the
closure with the container.

2. The tamperproof package set forth in claim 1
wherein said band comprises an annular wall of substan-
tially uniform thickness.

3. The tamperproof package set forth in claim 2
wherein said interengaging means between the closure
and the neck of the container comprise complementary
threads.

4. The tamperproof package set forth in claim 1, 2 or
3 wherein said band includes an integral panel con-
nected to the band by a weakened portion which may
be severed to produce a liner and thereafter displaced
into position adjacent the undersurface of the top wall.
5. A tamperproof plastic closure comprising
said closure having a top wall and a peripheral skirt,
and interengaging means for engaging the neck of
a container,
a separate plastic pilfer band,
axially engageable and disengageable interengaging
means between said band and said skirt operable
upon relative axial movement to engage and disen-
gage the skirt and band,
said band having radially inwardly extending por-
tions adapted to extend below a flange of a con-
tainer such that when the closure is applied to a
container, the band is flexed over the annular
flange of the container, and when the closure is
thereafter removed from the container, the band is
prevented from removal from the container and is
thereby disengaged from the closure,
said interengaging portions between said skirt of said
closure and said band comprising an annular notch
on the inner surface of said skirt facing radially
inwardly,
said band having an annular bead on the outer surface
thereof engaging said notch,
the outer diameter of the bead being greater than the
inner diameter of the portion of the wall having the
notch therein and being such that the band must be
compressed radially inwardly to apply the band to
the closure so that the band has an interference fit
with the skirt of the closure in order that in the
unrestrained position of said band, it cannot re-
engage with the skirt upon re-engagement of the
closure with a container.
6. The tamperproof closure set forth in claim 5
wherein said band comprises an annular wall of sub-
stantially uniform thickness.
7. The tamperproof package set forth in claim 6
wherein said interengaging means on the closure for
engaging the neck of a container comprises threads.
8. The tamperproof package set forth in claims 5, 6 or
7 wherein said band includes an integral panel con-
nected to the band by a weakened portion which may
be severed to produce a liner and is thereafter displaced
into position adjacent the undersurface of the top wall.
